SPINDLE MOUNTING

Francis E. Kelley, Providence, R. I., assignor to
Easton and Burnham Machine Company, a cor-
poration of Rhode Island

Application October 3, 1936, Serial No. 103,857

8 Claims. (Cl. 308—150)

This invention relates to improvements in oil damped spindle constructions; and has for one of its objects the provision of a spindle bearing of simple and improved construction which will be capable of reducing the objectionable vibrations of the spindle to progressively disperse and diffuse the same by the action of several separate cushioning effects of the liquid, all of which together will practically suppress and nullify the oscillatory or gyratory motion of the spindle and will result in a steady and smooth running spindle blade.

Another object of the invention is the provision of a spindle construction which will present less resistance to the running of the spindle, with a consequent reduction in power consumption for driving the device, and to provide a simplified spindle construction in which the bearings for the blade are separate from each other and located in different mounting members.

With these and other objects in view, the invention consists of certain novel features of construction, as will be more fully described, and particularly pointed out in the appended claims.

In the accompanying drawing:

Fig. 1 is a vertical cross-sectional view of a spindle constructed in accordance with this invention;

Fig. 2 is a detail transverse sectional view taken on the line 2—2 of Fig. 1;

Fig. 3 is a detail transverse sectional view taken on the line 3—3 of Fig. 1; and

Fig. 4 is a detail transverse sectional view taken on the line 4—4 of Fig. 1.

The common method of constructing spindles of this type, as heretofore practiced, has consisted in rotatably mounting the spindle blade within a tubular-bolster provided with the requisite bearing surfaces for supporting the blade laterally therein, and the spindle blade is stepped at its lower end in a bearing member carried by the lower end of the spindle bolster, the latter being located in an oil well formed in the bolster casting in which a clearance space is provided between the bolster and its casting sufficient to retain an oil film therein which will exert a cushioning effect upon the vibrating bolster for dampening harmful vibrations of the spindle blade caused by an unbalanced bobbin. However, all of these prior devices have not proven wholly satisfactory in actual use, due to the fact that while the film of oil disposed between the outer wall of the bolster and the casting side serves to greatly reduce the injurious effects set up by the vibration of the blade when in motion

yet they are not entirely absorbed or eliminated but still persist to such an extent as to interfere seriously with the manufacturing operations because the speed must be kept down in order to avoid frequent interruptions in the operation of the machine arising by breakage of the yarn or other product; and in order to overcome these difficulties, I provide a spindle mounting comprising two or more concentric tubular bolsters, fitted one within another around the spindle and located in the bolster casing, with a film of oil between each of the bolsters and between the outermost bolster and the casing for distributing the dampening or absorbing effect among the several oil films which conjointly act to completely cushion the vibrations of the spindle, and I have further provided a spindle construction in which the blade is rotatably mounted on two bearings, one consisting of an upper bearing sleeve located in the upper end portion of one bolster to laterally support the blade, while the other bearing member consists of a step which is secured in the lower end portion of another bolster; and the following is a more detailed description of the present embodiment of this invention, illustrating the preferred means by which these advantageous results are accomplished.

With reference to the drawing, wherein for the purpose of illustration is shown one specific embodiment of my invention, the numeral 10 designates a bolster casing having a flanged head member 12 adapted to be seated upon the upper face of a spindle rail, not shown, of a spinning or twisting frame. Depending below the flange 12 is a tubular body portion or stem 13 which is closed at its bottom to form an oil reservoir. The stem 13 is suitably provided with screw threads as indicated at 14 for receiving a clamping nut, not shown, to secure the bolster case to the spindle rail of the machine. Standing from the head flange 12 of the bolster casing is the usual upright oil-conveying spout arm 16 which is of well known construction and through which oil is poured and conducted to supply lubricant to the reservoir in the lower portion of the casing stem 13. The upper end of the spout 16 is closed by a hinged cover 17 having a laterally extending projection 18 which forms a detent positioned just above the top of the driving whirl 19 on the rotatable spindle 20 for retaining the latter against displacement from the bolster case. The spindle 20 may be of the usual construction having tapering end portions and an intermediate cylindrical section,

The bolster casing 10 also includes a short tubular extension 21 which projects upwardly from the head 12 and is in substantial alignment with the stem 13 to form the central longitudinal bore 22 of the bolster case. This extension 21 is located within an enlarged recess 23 of generally cylindrical shape and formed in the underside of the whirl 19, as is a well known construction in the art, so that the exterior part of the extension 21 is thus surrounded by the encircling and depending sleeve portions of the whirl sides. The whirl 19 is suitably secured to the spindle blade 20, as by a press fitting engagement therewith, and a grooved rim portion 25 is provided on the whirl to receive the usual driving belt or band, 15 not shown, for driving the spindle. All the structure as thus described is of old and well known construction and may obviously be varied according to standard types of spinning spindle constructions to which my invention is to be 20 applied.

To provide a fluid cushioning mounting for the spindle blade in the casing 10, I have provided an improved spindle dampening construction which, in the present embodiment of the invention, comprises a pair of concentric tubular bolsters 26 and 27 arranged in a nested formation one within the other in the bore 22 of the casing 10, the spindle blade 20 being entirely supported for rotation by two spaced bearing surfaces, 28 and 29 respectively, one of which is provided by each of the bolsters. Thus, the spindle blade is unsupported in the stretch between the two bearings. As illustrated in Fig. 1, the bolsters 26 and 27 are of unequal length, the latter being the 35 longer and extending upwardly along the bore 22 to a point close to its upper end, while the bolster 26 is located within the lower portion of the bolster 27 and extends upwardly along the bore thereof so that its upper end is in close proximity 40 to the flanged head 12 of the bolster case, and the lower portions of the telescopically arranged bolsters are located in the oil reservoir in the stem 13 of the bolster casing. The bolsters 26 and 27 are formed of such sizes that the inner bolster 26 will fit loosely within the outer bolster 27, and likewise the latter is loosely positioned in the bore 22 of the casing 10, thus providing a pair of longitudinally extending cylindrical clearance spaces 30 and 31 which each receive a film 45 of liquid in said reservoir to provide a series of progressive cushioning or dampening layers or columns of liquid alternately interposed between the respective bolsters and the casing for fractionally distributing and effecting a cushioning action upon the lower end of the spindle during vibration, oscillation or gyration of the same. The construction, thus described, thus permits 50 separate yielding movement of one bolster relative to the other and the casing in response to the oscillatory or gyrotatory motion of the spindle.

In the construction shown in Fig. 1 the bearings for supporting the spindle blade are shown, as consisting of a step 28 formed of a glass hard metal, preferably of hardened steel, and having in its top portion a recess 32 for mounting the tapered lower end of the spindle blade. The step 28 is suitably and tightly secured in the lower end of the bolster 26, and a pin 33 is fastened in the bearing 28 and passes diametrically through the 55 wall of the bolster 26 and into an enlarged opening 34 formed in the wall of the bolster 27. An opening 35 extends diametrically through the 60 wall of the bolsters 26 and 27 and perforates the 65 walls of the bolsters 26 and 27 and provides a transverse duct through 70 the bolsters 26 and 27.

which the oil contained in the reservoir has access to the lower bearing for the spindle. By reason of this construction, it is possible for one to withdraw both bolsters together as a unit from the bore of the casing 10, besides fixedly connecting both bolsters and the step bearing to prevent relative turning of the parts during running of the spindle. A suitable lug 36 projecting from the side of the bolster 27, adjacent to its upper end fits into a longitudinal groove 37 formed in the inner peripheral surface of the extension 21 for retaining the outer bolster 27 against rotation with the spindle.

The upper bearing 29 which serves to support the blade laterally consists of a sleeve which may be composed of a glass hard metal, preferably of hardened steel, and is tightly secured in the top end portion of the bore of the outer bolster 27 for engaging the usual cylindrical section of the spindle blade. If desired, it is feasible to utilize for the upper and lower bearing 29 and 28 respectively, the special bearing constructions made of chrome tool steel having substantially glass hard bearing surfaces, as more fully disclosed and described in my prior Patent No. 2,041,934, granted May 26, 1936, to which reference may be had for a more detailed description.

Formed in the side surface of the upper bearing 29 is a longitudinal groove 38 which communicates with the space below the bearing 29 to permit the oil which is forced up the clearance space 31 by the pumping action of the vibrating spindle and bolsters and be discharged into the space in the upper end of the extension 21 to flow downwardly into the space in the lower portion of the casing 10 surrounding the spindle blade.

In the operation of the spindle, the cushioning or dampening effect is obtained by reason of the fact that the clearance spaces 30 and 31, which are filled with oil, provide a series of oil films which supplement one another to graduate and progressively distribute and suppress the vibrations of the spindle which tends to oscillate about the middle of bearing 29 as a pivot center so that they become progressively decreased in effect by the several films and finally reduced to a minimum by the combined effect of both oil films as to be practically absorbed by the cushioning effect. This belt assists in holding the whirl portion of the spindle rigid against movement and contains within it a point which is the center of such oscillatory movement which exists.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In combination, a spindle blade, a bolster casing, a plurality of bolsters in said casing, a pair of spaced bearing members for said blade, one of said bearings being secured in the upper part of the outer bolster and the other bearing being secured at the lower portion of the inner bolster, said bolsters being fitted one within another in spaced relation and located in said casing spaced therefrom each movable relative thereto and with their lower ends resting on the inner bottom surface of said bolster case.

2. In combination, a spindle blade, a bolster casing having an oil reservoir, a plurality of bolsters in said casing, a pair of spaced bearing

members for said blade, one of said bearings being secured in the upper part of the outer bolster and the other bearing being secured in the lower portion of the inner bolster, said bolsters being fitted one within another and movable relative to each other and relative to the casing and spaced from each other and having their lower portions located in said reservoir to provide an oil film between said bolsters and said bolster casing and with their lower ends resting on the inner bottom surface of said bolster case.

3. In combination, a spindle blade, a bolster casing having an oil reservoir, at least two bolsters in said casing, a pair of spaced bearing members for said blade, one of said bearings being secured in the upper part of the outer bolster and the other bearing being secured in the lower portion of the inner bolster, said bolsters being fitted one within the other and spaced from each other and free to move relative to each other and relative to said casing and having their lower portions located in said reservoir to provide an oil film between said bolsters and said bolster casing and with their lower ends resting on the inner bottom surface of said bolster case.

4. In combination, a spindle blade, a bolster casing having an oil reservoir, a plurality of bolsters in said casing, a pair of spaced bearing members for said blade, one of said bearings being secured in the upper part of the outer bolster and the other bearing being secured in the lower portion of the inner bolster, said bolsters being fitted loosely within one another to provide separate clearance spaces between each bolster and the outer bolster and the casing and movable therein and with the lower end portions of the bolsters extending into said reservoir to provide an oil film in each of said clearance spaces whereby said films act together to cushion the vibratory motion of the spindle, the lower ends of said bolster resting on the inner bottom surface of said bolster casing.

5. In combination, a spindle blade, a bolster casing having an oil reservoir, a pair of loosely telescopically arranged bolsters loosely mounted in said casing, spaced bearings for said blade, said bolsters being of unequal length and having their lower end portions located in said reservoir, and with their lower ends coextensive and resting on the lower wall of said reservoir, the longer of the bolsters having the upper bearing for said blade secured therein and the blade being stepped on the lower bearing which is secured in the lower end of the shorter bolster.

6. In combination, a spindle blade, a bolster case, a bolster loosely mounted in said bolster case, a second bolster shorter than the first bolster loosely mounted within said first bolster, the lower end of each of said bolsters being coextensive at the bottom and resting on the inner bottom surface of said bolster case, and bearings for said spindle blade within said bolsters, one of said bearings being within the said first bolster only and above the second bolster and providing a rockable mounting for the blade about an axis adjacent to the upper bearing, the walls of said bolsters being spaced from each other and from the inner walls of said bolster casing throughout their entire length.

7. In combination, a spindle blade, a bolster case, a plurality of bolsters loosely mounted within said bolster case and loosely mounted one within another, said bolsters being of unequal length with the lower ends of said bolsters being coextensive at the bottom and resting on the inner bottom surface of said bolster case, and bearings for said spindle blade between said spindle blade and bolsters, the upper of said bearings being within one of the bolsters and above the upper end of another of said bolsters said bearings providing a rockable mounting for the blade about an axis adjacent to the upper bearing, the walls of said bolsters being spaced from each other and from the inner walls of said bolster casing throughout their entire length.

8. In combination, a spindle blade, a bolster casing, a bolster loosely mounted in said bolster case, the inner diameter of said casing being substantially uniform throughout the length of said bolster and the outer diameter of said bolster being substantially uniform throughout its length to provide a substantially uniform spacing of said casing and bolster, a second bolster shorter than the first bolster loosely mounted within said first bolster, the inner diameter of said first bolster being substantially uniform throughout the length of said second bolster and the outer diameter of said second bolster being substantially uniform throughout its length to provide a substantially uniform spacing of said bolsters, the lower ends of said bolsters being coextensive at their bottom and resting on the inner bottom surface of said bolster case, and bearings for the spindle blade within said bolsters, one of said bearings being secured in the upper part of the outer bolster and the other bearing being secured in the lower part of the inner bolster.

FRANCIS E. KELLEY.
